MAGNETIC CATCH ASSEMBLY

Howard G. Tresemer, Rockford, Ill., assignor to National Lock Co., Rockford, Ill., a corporation of Delaware
Filed June 30, 1966, Ser. No. 561,779
2 Claims. (Cl. 292—251.5)

ABSTRACT OF THE DISCLOSURE

A magnetic catch assembly with an integral plastic housing having an integral stud centrally positioned in the housing and adapted to receive through an opening in the housing a rectangular shaped magnet and a pair of pole pieces, each of which have a central opening loosely receiving the stud, the housing having a pair of integral tabs to retain the magnet and pole pieces in the housing, with the housing also having an integral rib aligned with the stud to provide a fulcrum for pivotal movement of the pole pieces relative to the housing to properly engage a strike surface.

The present invention relates to a novel door catch and more particularly to a magnetic catch assembly for a door or other closure.

Among the objects of the present invention is the provision of a magnetic catch assembly having a housing formed of a relatively stiff but resilient or elastic plastic composition material having a recess to receive a magnet and its associated pole pieces therein. The housing includes a pair of inwardly extending retaining tabs integral therewith which retain the magnet and pole pieces within the recess; the housing having sufficient resilience so that the wall with the retaining tabs may be flexed apart to allow the magnet and pole pieces to pass by the tabs and enter the recess.

Another object of the present invention is the provision of a magnetic catch assembly having a housing with integral retaining tabs having retaining surfaces and converging camming surfaces thereon. When the magnet and pole pieces are inserted into the recess in the housing, they engage the camming surfaces of the tabs to urge the tabs and walls apart allowing the magnet and pole pieces to enter the recess; the tabs snapping back into position with the retaining surfaces over the members to retain them in the recess.

A further object of the present invention is the provision of a magnetic catch assembly having a housing with a recess and an integral stud centrally mounted in the recess. The magnet and the pole pieces all have a generally central opening therein to receive the stud so that the magnet and pole pieces are loosely mounted in the housing for individual free adjustment or pivotal movement therein around the axis of the stud.

Further objects are to provide a construction of maximum simplicity, efficiency, economy and ease of assembly and operation, and such further objects, advantages and capabilities as will later more fully appear and are inherently possessed thereby.

In the drawing:

FIGURE 1 is a rear elevational view of the magnetic catch assembly of the present invention.

FIG. 2 is an end elevational view of the magnetic catch assembly taken from the right side of FIG. 1 and showing the assembly secured to a partition or wall.

FIG. 3 is a front elevational view of the magnetic catch assembly.

FIG. 4 is an exploded perspective view of the magnetic catch assembly showing the components disassembled.

Referring more particularly to the disclosure in the

drawing wherein is shown an illustrative embodiment of the present invention, FIG. 4 discloses a magnetic catch assembly 10 with its components disassembled and including a housing 11, a permanent magnet 12, and a pair of metal pole pieces 13 and 14 at the opposite sides of the magnet. The magnet 12 has a generally central opening 15 and is generally of less width than the pole pieces. The pole pieces 13 and 14 each have an opening 16 which is central as to the length of the pole piece but slightly centrally offset of its width.

The housing 11 has a centrally offset portion 17 having a cavity or recess 18 open at the rear and along one side or edge to loosely receive the magnet 12 and pole pieces 13 and 14, and oppositely extending mounting flanges 19 having elongated openings 21 for receiving suitable securing means, such as screws 22, to anchor the housing 11 in adjusted position to an anchoring surface such as a partition or wall 23. Extending inwardly into the cavity or recess 18 from the rear edge of the flange 19 is a pair of inwardly projecting retaining tabs 24 each having a retaining surface 25 and an inwardly converging camming surface 26. The central portion 17 of the housing 11 has an opening 27 into the recess 18 in one end wall of the housing adjacent the tabs 24.

The cavity 18 loosely receives the magnet 12 and pole pieces 13 and 14 therein as seen in FIGS. 1, 2 and 3, and a stud or shaft 28 integral with the housing 11 extends rearwardly from the front wall 29 of the housing to terminate at the plane of the rear surface of the housing and flanges. The stud 28 is loosely received in the opening 15 in the magnet 12 and in the openings 16 in the pole pieces 13 and 14 to operatively align these members in the housing 17. A rib 31 is formed on the inner surface of housing wall 32 to provide a fulcrum about which the pole pieces 13 and 14 pivot so that the edges 33 of the pole pieces protruding beyond the outer or adjacent edge of the magnet can automatically adjust to the strike surface. The pole pieces 13 and 14 also are adapted to adjust individually with the recess 18 being sufficiently larger than the periphery of the pole pieces 13 and 14 to allow for this free adjustment or pivotal movement.

To assemble the components of this catch assembly 10 in the housing 11, the latter is centrally flexed to spread and move the tabs 24 apart and then the pole piece 13, magnet 12 and the pole piece 14 are dropped over the stud 28 into the cavity or recess 18. The housing 11 is then released and the magnet 12 and pole pieces 13 and 14 are retained in the catch by the surfaces 25 of the retaining tabs 24. If the tabs 24 are not spread sufficiently far apart by flexing the housing during such assembly, the outer edges of the pole pieces will engage the beveled surfaces 26 to cam the tabs 24 to allow the pole pieces and magnet to enter the cavity or recess and be retained therein by the tabs.

Having thus disclosed the invention, I claim:

1. A magnetic catch assembly consisting of an integral plastic housing having a closed front wall and side walls defining a central cavity and having a rear opening and a side wall opening into the cavity, oppositely extending mounting flanges on said housing, an integral stud centrally positioned in said cavity and extending inwardly from said front wall of the housing to the rear opening therein, a magnet and a pair of pole pieces each of rectangular shape positioned in said cavity with the pole pieces on opposite sides of the magnet with one edge only of said pole pieces extending outward through the side wall opening beyond the housing to engage a strike surface, the magnet and the pole pieces each having a generally central opening loosely receiving said stud, and retaining means integral with said housing retaining the magnet and pole pieces within said cavity including

a pair of oppositely disposed inwardly extending tabs integral with but of substantially less length than the opposed side walls of the housing, said tabs being positioned adjacent the side opening of the housing to extend into the rear opening thereof, each tab having an inner planar retaining surface perpendicular to the side wall and an outer beveled camming surface.

2. A magnetic catch assembly as set forth in claim 1, in which an integral rib is centrally positioned on the inner surface of the side wall opposite the side wall opening and aligned with the stud to provide a fulcrum for pivotal movement of the pole pieces relative to the housing to properly engage a strike surface.
